UNITED STATES PATENT OFFICE

2,143,807

FILL-LEVELING AND OVERLOAD-REMOVING DEVICE

George R. Stuart, Knoxville, Tenn.

Original application June 9, 1937, Serial No. 147,342. Divided and this application November 22, 1937, Serial No. 175,966

7 Claims. (Cl. 226—22)

This invention relates to improvements in filling and closing portable receptacles and more particularly to an improved device for leveling the filled material in a receptacle, and removing any overload therefrom, prior to capping of the receptacle.

The subject matter of the present invention forms a division of my co-pending application Serial Number 147,342, filed June 9, 1937.

An important object of the invention is to provide an improved fill-leveling and overload-removing device operable by a rotary or spinning motion.

Another object is to provide a device which will level the fill and remove any overload beyond a plane within and parallel to the circular mouth end of a container.

A further object is the provision of a fill-leveling and overload-removing spinner having an improved housing so formed as to facilitate manual positioning of a container in correct co-operative relation to the spinner.

A still further object of the invention is to provide an improved spinner having a housing which is formed as to confine the overload or surplus material against escape other than in a downward direction whereby to permit operation of the spinner at a high rate of speed without promiscuous scattering of the surplus material.

Still another object is to provide an improved device as described which is relatively simple, safe and sanitary.

Other objects and advantages of the invention will be apparent from the following detailed description, taken in connection with the accompanying drawing, forming a part of this specification, and in which drawing:—

Figure 1 is a fragmentary perspective view of the improved fill-leveling and overload-removing device.

Figure 2 is a vertical sectional view of the device, and showing the manner of manually positioning a filled container in cooperative relation to the device.

In the drawing, which for the purpose of illustration shows a preferred embodiment of the invention, and wherein similar reference characters denote corresponding parts throughout the views, the letter A may generally designate the improved device for leveling the fill and removing the overload from a suitable circular container B.

The device A may include a shaft 10 having reduced ends 11 and 12, which may be provided with right and left-hand threads respectively. Intermediate its ends, the shaft may be rotatably

supported, as by spaced-apart bearings 13, on opposite sides of a suitable pulley 14, fixed to the shaft, as by a set screw 15, and connected, as by a belt 16, to any suitable source of power, such as an electric motor (not shown). Secured at opposite ends 11, 12 of the shaft 10, as by coaxial right-hand and left-hand internally threaded bosses 17, 18 respectively, and projecting from the inner end faces 19 are cylindrical disc-like spinners 20, 21 provided at their outer end faces 22 with inwardly convergent frusto-conical annular rims 23 terminating in annular seats 24 against which the circular mouth ends of containers, such as the container B shown in Figure 2, may be positioned. Each spinner is provided with a radially disposed cutting and leveling blade 25 positioned between the annular seat 24 and the axis of the spinner, and projecting obliquely outwardly from the plane of the annular seat 24 with its free end forming a cutting edge 26 facing in the direction of rotation of the spinner. Turning of the shaft 10 in a given direction will, of course, rotate one spinner 20 in a counter-clockwise direction and the other spinner 21 in a clockwise direction. Adjacent the leading side of each blade 25 is a slot 27 extending thru the spinner and forming an outlet passageway therethrough for conducting excess material from the container B to the inner end face 19 of the spinner. The slot 27 may terminate at its inner end in an oblique surface 28 extending from the axis of the cylindrical member at its juncture with the boss, and which may be formed by obliquely cutting away a portion of the boss adjacent the cylindrical member.

Over each spinner is secured, as by cap screws 29, a housing 30 provided with an inwardly convergent frusto-conical annular recess wall 31 terminating in an aperture 32 encircling the spinner adjacent its outer end face. Each housing may also be provided with a suitable opening 33 for accommodating the shaft 10. While each housing at its upper end portion 34 may comprise a cylindrical portion 35 and a frusto-conical portion 36, the lower end of the housing preferably depends to form a chute-like skirt 37 having an opening 38 in its base through which excess material 39 may fall into a suitable container 40 therebeneath.

In the operation of the improved device, containers, such as the container B, after being filled by any suitable means (not shown) may be manually positioned one by one with their circular mouths in contact with the annular seats 24 of the spinners 20, 21, the blades 25 of which will thereupon extend radially within the mouths 55

of the containers and will remove any excess material 39 beyond the predetermined level of fill within and parallel to the circular mouth ends of the containers. The excess material positioned 5 in advance of the obliquely disposed blades 25 will pass thru the slots 27 to the inner faces 19 of the spinners and will fall thru the openings 38 of the skirts 31 into the container 40. As two spinners are provided, one at each end of 10 the shaft 10, two operators may be employed, if desired, each at an opposite end of the device. The cone-like surfaces of the rim 23 and recess wall 31 will tend to center the containers with respect to the annular seats 24, thereby facilitating 15 the manual positioning of the containers in cooperative relationship to the device. As the blades 25 are positioned well within the outer limits of the spinners and spinner housings, the device may be safely operated at a high rate 20 of speed, and the housing will direct the overload or surplus material downwardly so as to counteract any tendency of the surplus material to fly from the spinners under the influence of centrifugal force.

25 Various changes may be made to the form of invention herein shown and described, without departing from the spirit of the invention or the scope of the following claims.

I claim:

30 1. In a device for leveling material in a container and removing any excess material therefrom, a rotatable shaft, a cylindrical member having one end face co-axially secured to an end of the shaft and provided at its opposite end face 35 with an annular marginal seat, against which the container may be positioned, a blade carried by said opposite end face inwardly of said seat, and projecting from said opposite end face so as to extend into the container positioned against said 40 seat, for cutting away excess material in the container, said cylindrical member being provided with a slot extending inwardly from the marginal seat to the axis of said cylindrical member and forming an outlet passageway through 45 the cylindrical member for removing excess material from the container as it is cut away by said blade.

2. In a device for leveling material in a container and removing any excess material therefrom, a rotatable disc provided with an annular marginal seat against which the container may be positioned, a radially disposed blade carried by the disc inwardly of said seat and projecting from the disc so as to extend into the container 50 positioned against said seat, for leveling the material in the container and cutting away any excess material, and a radial slot in the disc adjacent the blade forming an outlet passageway through the disc for said excess material.

60 3. In a device for leveling material in a container and removing any excess material therefrom, a rotatable perforated disc carrying a material-leveling blade and provided with an annular marginal seat, against which the container

may be positioned, and a housing for said disc having an inwardly convergent conical seat terminating in a circular aperture bounding the seat of said disc, for guiding said container into contacting relation with said seat of said disc.

4. In a device for leveling the fill within and removing any overload from a container having a circular mouth end, a cylindrical member mounted for axial rotation and provided at one end with an axial frusto-conical recess relatively wider at 10 its mouth than the mouth end of the container and converging at its inner end whereby to form a seat against which the mouth end of the container may be positioned, and a blade carried by the cylindrical member within the recess and extending radially of the mouth end of the container 15 when the container is positioned against the seat.

5. In a device for leveling the fill within and removing any overload from a container having 20 a circular mouth end, a cylindrical member mounted for axial rotation in a given direction and provided at one end with an axial frusto-conical recess relatively wider at its mouth than the mouth end of the container and converging 25 at its inner end whereby to form a seat against which the mouth end of the container may be positioned, and a blade carried by the cylindrical member within the recess, said blade having an edge leading in said given direction and extending 30 radially of the mouth end of the container when the container is positioned against the seat, said cylindrical member being provided with an outlet leading from a zone of the recess adjacent that portion of the blade facing in said given direction. 35

6. In a device for leveling the fill within and removing any overload from a container having a circular mouth end, a cylindrical member mounted for axial rotation and provided at one end with an axial frusto-conical recess relatively 40 wider at its mouth than the mouth end of the container and converging at its inner end whereby to form a circular seat against which the mouth end of the container may be positioned, fill leveling and overload removing means carried by the cylindrical member intramarginally of the circular seat, and a housing for the cylindrical member provided with a circular opening co-axial with and bounding the mouth of said frusto-conical recess of the cylindrical member.

7. In a device for leveling the fill within and removing any overload from a container having a circular mouth end, a circular member mounted for rotation about its axis and provided with a circular seat against which the mouth end of the container may be positioned, a blade carried by the circular member intramarginally of the seat, and a housing for the circular member provided with a frusto-conical recess co-axial with the circular member and relatively wider at its mouth 55 than the mouth end of the container and converging at its inner end whereby to guide the mouth end of the container towards said seat.

GEORGE R. STUART.
